(57) **CLAIM**

The ornamental design for a sensor cover as shown and described.

DESCRIPTION

FIG. 1 depicts a front, top, left perspective view of a sensor cover showing our new design.

FIG. 2 depicts a front, bottom, right perspective view thereof.

FIG. 3 depicts a front view thereof (and the back view is omitted as the back of the sensor cover is not claimed and the back view does not show any additional portion of the design).

FIG. 4 depicts a left side view thereof; and,

FIG. 5 depicts a right side view thereof.

The dash lines depict portions of the article forming no part of the claimed design.
